UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

SEAM FOR SEWED ARTICLES.

1,306,110.

Specification of Letters Patent. Patented June 10, 1919.

Application filed February 6, 1918. Serial No. 215,681.

To all whom it may concern:

Be it known that I, GEORGE S. GATCHELL, a citizen of the United States, residing at Roselle Park, in the county of Union and 5 State of New Jersey, have invented certain new and useful Improvements in Seams for Sewed Articles, of which the following is a specification, reference being had thereto in the accompanying drawings.

10 This invention relates to edge-finishing seams for sewed articles, and more particularly to edge-finishing seams for garments made from knit goods. An object of the invention is to provide a neat and 15 durable edge-finishing seam which will remain in its original flat condition so as not to irritate the wearer of the garment and which will possess sufficient strength and body to resist the various strains to which 20 it is likely to be subjected.

While it has heretofore been proposed to give additional strength and body to an edge-finishing seam by incorporating a reinforcing ply therein, as by folding back 25 an edge-portion of material on the main body-portion thereof and overseaming the edge-fold, the product has been unsatisfactory as in some instances the inner or raw edge of the reinforcing or folded over 30 ply has not been covered, and in others the reinforcing ply, although covered, has been left free to curl up within the confines of the overseam and form an objectionable welt or ridge. As seams of this general type 35 are commonly employed to finish the edges of under-garments made from knit goods and particularly the free edges of the seat-flaps of union-garments, it is of course desirable that the seam possess sufficient body 40 to resist permanent distention, distortion or other strains, and that it be constructed to remain flat so as not to irritate the wearer.

According to the present invention an edge-finishing seam is produced wherein a 45 relatively narrow or reinforcing ply is superimposed upon a main ply so as to extend along the edge of the latter. Covering seam-forming stitches of any suitable character are utilized to anchor the reinforcing ply to the main ply between the inner and outer edges of said reinforcing ply and to cover the inner or raw edge of the latter. Preferably the reinforcing ply is formed by folding back the raw edge-portion

of fabric although a separate reinforcing strip may in some instances be used.

In the accompanying drawings Figure 1 is a plan view of one side of a body-fabric embodying the invention in its preferred form. Fig. 2 is a plan view of the reverse 60 side of the seam illustrated in Fig. 1. Fig. 3 is a cross-section of the seam illustrated in Figs. 1 and 2. Figs. 4, 5 and 6 are diagrammatic cross-sectional views of modifications of the invention.

In the preferred embodiment of the invention, as illustrated in Figs. 1, 2 and 3, the main body-fabric portion or ply 1 of material presenting an edge 2 has superimposed upon it a reinforcing ply or relatively 70 narrow strip of material 3 whose outer edge 4 is disposed in juxtaposition with the outer edge 2 of the main ply 1. In the embodiment illustrated in Figs. 1, 2 and 3 the superimposed outer edges 2 and 4 are connected by the line of fold 5 or, in other words, the main ply 1 has its edge-portion folded back upon the face of the main ply along the line of fold 5 to form an edge fold 65 or narrow reinforcing ply 3.

Covering seam-forming stitches, preferably such as disclosed in my copending application Serial No. 185,446, filed August 10, 1917 and constituting a four-needle modification of the seam disclosed in the patent to 80 Munsing, No. 506,524, of October 10, 1893 are utilized to substantially and preferably wholly inclose the reinforcing ply 3 and 85 cover the inner edge 6 of the latter. These covering stitches comprise the needle-threads 7, 8, 9 and 10 which are formed at 90 intervals into needle loops 7', 8', 9' and 10', respectively. The loops 7' of the inner row extend through the main ply 1 adjacent the inner edge 6 of the reinforcing ply 3. The 95 needle-loops 10', constituting the outer row, do not pass through body-fabric material or, in other words, are formed "in the air" and serve as overedge threads for the edge-fold 5. The loops 8' and 9' of the intermediate rows enter the reinforcing ply 3 between the edges 4 and 6 thereof and anchor it to the main ply 1, thereby holding the reinforcing ply flat against the main ply 100 and preventing its curling up between the inner and outer rows of needle-loops. One or more cross-threads or covering threads such as shown at 11 and 12 are looped back-

and-forth under the longitudinally extending portions of the needle-threads as illustrated in Fig. 2. The looper-thread 13 which is also a covering thread, is concatenated with the needle-loops in the usual manner, as shown in Fig. 1, and serves to key or lock said loops, whereby said loops may be considered as constituting keyed penetrative thread-loop structures which enter the relatively narrow or reinforcing ply 3 of material and anchor it between its edges to the main ply 1.

It will be seen that in the modification shown in Figs. 1, 2 and 3 the reinforcing ply is wholly inclosed by the threads of the covering seam and that the folded back edge-portion of material is stitched down flat to the face of the body fabric and thereby prevented from curling up or forming an objectionable ridge within the confines of the seam. Moreover the edge 6, which usually is a raw edge, is effectively covered and the edge-fold 5 is neatly overseamed. A seam of the character described will be seen to possess sufficient body to hold its shape and withstand the various strains to which it is likely to be subjected. It is so constructed as to maintain its flat and neat appearance indefinitely.

The various modifications of the invention, illustrated in Figs. 4 to 6 inclusive, will also be seen to possess novel characteristics such as above mentioned. Fig. 4 shows a construction similar to that shown in Figs. 1, 2 and 3 but having three needle-threads 14, 15 and 16 formed as usual into loops which are concatenated with the looper-thread 17 and bind down the cross thread or threads 18. The loops of the needle-thread 14 pass through the main ply 19 only. The loops of the needle-thread 15 anchor the narrow or reinforcing ply 20 between its edges to the main ply 19 and the loops of the needle-thread 16 are formed "in the air" and serve as overedge threads at the line of fold in the same manner as the loops of the needle-thread 10 in the modification illustrated in Figs. 1, 2 and 3. The construction shown in Fig. 5 is similar to that shown in Fig. 3 except that the material at the line of fold 21 is not covered by the row 21^x of needle loops, although said needle-loops are located at the line of fold

or, in other words, at the outer edge of each of the superposed plies. The reinforcing 55 ply 22 is therefore covered substantially throughout its width by the covering thread 22^a of the seam. Fig. 6 merely shows a three-needle modification of the four-needle seam illustrated in Fig. 5.

The invention is not to be considered as limited to the specific forms shown and described but may obviously be otherwise embodied within the spirit of the invention defined in the appended claim. The above 65 embodiments therefore, should not be regarded as exhausting the possible modifications of the invention. The particular arrangement or concatenation of the threads of the covering seam is also immaterial to 70 the present invention. The gist of the invention is the use of a covering seam of at least three needle threads to bind and anchor an edge-fold to a main ply of material; the seam including portions of thread 75 which extend across the seam and cover the raw edge of the edge-fold as well as the exposed face of the edge-fold. The cross thread portions need not necessarily be formed by threads additional to the needle-threads, but it is essential that an intermediate needle-thread be formed into loops 80 penetrating the edge-fold between its edges and serving to anchor it to the main ply.

Having thus set forth the nature of the 85 invention, what I claim herein is:—

An edge-finishing seam for sewed articles comprising a main ply of material having a free and unattached marginal portion folded back upon the face of said main ply to form a reinforcing ply, a first needle-thread formed at intervals into loops passing through the main ply only adjacent the inner edge of the reinforcing ply, a second needle-thread formed at intervals into loops 90 passing through said reinforcing and main plies; and a third needle thread formed at intervals into loops substantially at the line of fold, said seam including upper and lower thread portions extending transversely of the line of seam-formation and held in contact relation with said main and reinforcing plies.

In testimony whereof, I have signed my name to this specification.

GEORGE S. GATCHELL.
